UNITED STATES PATENT OFFICE.

GEORGE S. NEWTON, OF WAUPUN, AND FREDERICK ZOLLNER, OF RANDOLPH,
WISCONSIN.

IMPROVEMENT IN PEAT-CUTTERS.

Specification forming part of Letters Patent No. 170,184, dated November 23, 1875; application filed
July 6, 1875.

To all whom it may concern:

Be it known that we, GEORGE S. NEWTON, of Waupun, and FREDERICK ZOLLNER, of Randolph, in the county of Dodge, in the State of Wisconsin, have invented certain Improvements in Peat-Cutters, of which the following is a specification:

The object of our invention is to cut peat from a bog, and raise and lay out the same, by the combination, in a peat-machine, of a cutter and box to hold the peat, arranged on a vertical shaft, with rack and pinion to raise and lower the same, with a carriage-way to convey the shaft and peat-box to the side of the machine, when the peat is emptied out of the box and carried away to dry.

The following is a description of the drawing forming part of this specification:

Figure 1, Sheet 1, is a front view of our invention. Fig. 2, Sheet 1, is a plan view of the machine. Fig. 3, Sheet 2, is a side view of the machine, and Fig. 4 is a sectional view through the center of the machine; Fig. 5, a sectional view of shaft W and f'.

A is the frame of the cutter; B, the wheels under the peat-cutter, and on which it is moved from place to place; C, vertical shaft, with the peat-box and cutter attached to the bottom of same; D, the box which the peat is forced into as the shaft C descends; E, the sharp cutting-edge which cuts the peat on the bottom of the box D; F, a door to box D, which is opened after the box is raised, for the purpose of letting the peat fall out. This door fits into the bottom of the box D, and at the top is held in place by a hinged hasp, G, which swings down over a staple or latch, H, which passes through a hole in the hasp, and a pin, I, passes through the staple and holds the hasp firmly, and keeps the door closed; K, a hinged knife forming a stop at the bottom of the box, which, when the peat-box is shoved down and filled with peat, is shoved in and cuts off the peat, and holds it in the box; L, a pulley in a way, which the knife-handle works in, behind which a rope, M, passes, one end of which is attached to the knife-handle, and the other end attached to an axle of a wheel, N, which is hung in bear-

ings out from the top of box D; and when the box D is down in the peat-bog the wheel N is turned by a crank-pin in it, and the rope M is wound round the shaft, and the knife is forced into the bottom of the box, and cuts and holds the peat in the box, so that it shall be raised with the box when the shaft C is raised; O, rollers secured to standard T, running in ways P, which sustain the shaft C; Q, rack on shaft C, which pinion R meshes into to raise and lower the shaft; S, wheel on the end of shaft, on which pinion R runs; T, a standard on the front of frame A, on which shaft C works; U, a pulley on the top of standard T, over which rope U runs, one end of rope U attached to the top of shaft C, and the other end of same around shaft W, which is supported by boxes X secured to the frame A. The shaft on which pinion R runs operates in boxes secured to standard T. On the journals inside of the boxes X, which sustain the shaft W, are bevel-pinions, which work loosely on said journals; and on the inside of those bevel-pinions are teeth Z, into which a pin, A', on the shaft W catches when the shaft is shoved endwise, and revolves the pinion on the forward end of the shaft; B', a lever, one end of which is fastened to the frame A, and the other end resting on an arm, C', and a couple of pieces of metal, D', forming the center of the lever B', clasped round shaft W, between two shoulders on the shaft; and with this lever the shaft W is moved endwise in either direction, and a pulley, E', on the shaft W, by which, with a belt, power may be applied, and on the sides of the machine are a couple of shafts, F', with bevel-pinions G' on their ends meshing into pinions on shaft W; and when the shaft W is moved in either direction the pins A' will be meshed into the teeth Z, and revolve the shaft F' on whichever side it may be; and on the frame A are pulleys H', behind which a rope, I', runs to the standard T, and the other end of rope I' runs through a snatch-block, Z', and round one of the shafts F', so that as either shaft is revolved it will pull on the rope attached to it, and pull the standard T and shaft C to the side of the machine, for the

purpose of emptying the peat from box D, or carrying it back after being emptied for another load.

The operation is as follows: The machine being set where it is wanted to work the shaft C is placed over the place where the peat is to be cut, and the shaft is run down by the rack and pinion R, and the box will be filled; then force in the knife E and cut the peat, and hold the same in the box; then take hold of the end of rope U, if the machine is operated by power, and pull on same, and the shaft C will be raised and with it the box; then take hold of lever B' and move the shaft W, so that pin A' shall catch into the teeth on pinion, and the shaft and box with the peat will be hauled on the ways P to the side of the machine; then take out pin I and turn

up the hasp, and take out door F, and the box D can tip down. The hinge will permit it to do so, and the peat will be emptied out of the box; then carry the box and shaft back for another load.

We claim as our invention—

1. Box D, door F, swinging hasp G, staple H, and pin I, in combination with knife K, substantially as described.
2. Shaft C, pinion R, wheel S, rollers O, and ways P, in combination with box D, substantially as specified.

GEORGE S. NEWTON.
FREDERICK ZOLLNER.
